UNITED STATES PATENT OFFICE.

EDWIN CROMPTON AND CHARLES L. CROOKS, OF PUEBLO, COLORADO, ASSIGNEES TO THE POSITIVE-LOCK COMPANY, OF PUEBLO, COLORADO, A CORPORATION OF COLORADO.

LATCH.

Application filed October 5, 1922. Serial No. 592,497.

To all whom it may concern:

Be it known that we, EDWIN CROMPTON and CHARLES L. CROOKS, citizens of the United States, residing at Pueblo, county of Pueblo, State of Colorado, have invented certain new and useful Improvements in Latches; and we do hereby declare the following to be a full, clear, and exact description of the invention, such as will enable others skilled in the art to which it appertains to make and use the same.

This invention relates to latches, and particularly to types of latches especially adapted for use on doors and windows of vehicles such as automobiles. However, while latches embodying our invention are especially adapted for use on vehicle doors and windows, it is to be understood that our invention is in no sense limited to this particular utility. The term latch is used broadly to include both lock and latch constructions.

Vehicle doors, especially automobile doors, are generally subjected to severe vibration. Even if the parts are carefully fitted and door bumpers used, the vibration is generally sufficient to cause friction between the door and the frame, resulting in annoying squeaking and rattling when the vehicle is running. This is true even where the door bumpers extend out so far that the door can only be latched by closing it with a hard slam. In addition to the wear from these sources, the door and latch parts are subjected to much rough usage and many strains and stresses. All this results in loose-fitting connections with the attendant annoyance of squeaking and rattling.

An object of this invention is to provide a latch which will readily yield to receive the bolt or catch to be latched when closing the door, making it unnecessary to slam the door to close it and thus avoiding undue shock and strain on the parts of the door and latch.

Another object of the invention is to provide a latch in which substantially all play between the parts is automatically taken up and which will cooperate with the latch bolt or catch to hold it positively and firmly on all sides to prevent the door or latch parts from rattling and reducing wear of the parts to a minimum.

A further object of the invention is to provide a latch which, while having all the advantages heretofore mentioned, may be easily operated to readily release the cooperating latch bolt or catch.

The above and other objects and novel features of this invention will be apparent from the following description taken in connection with the accompanying drawings which illustrate one form of latch construction embodying our invention.

In the drawings,

Fig. 1 is a side elevational view of a latch construction embodying our invention, the same being shown with its cooperating latch bolt or catch in the position which the parts occupy when mounted on the door and door jamb, respectively, of an automobile, part of such door and door jamb being shown in dotted lines. In this view, the latch parts are shown in open or released position. In this position, the door is ready to be opened.

Fig. 2 is a side elevational view of a latch construction embodying our invention similar to that shown in Fig. 1, but with the latch parts shown in normal or closed position and the end portion of the latch shown in section on the line 2-2 of Fig. 3.

Fig. 3 is a sectional view taken on the line 3-3 of Fig. 2 looking in the direction of the arrows.

Fig. 4 is an end view looking in the direction of the arrow 4 in Fig. 2, the parts being in closed position with the catch or bolt, shown in section, in position in the latch.

Fig. 5 is an end view, similar to Fig. 4, but with the end plate broken away on line 5-5 of Fig. 1 and the parts in open position.

Fig. 6 is a plan view of the bolt or catch. Broadly stated, our invention comprises latching means yieldable to receive and hold a bolt or catch to be latched, means for clamping said bolt in engagement with said latching means, and means for operating the latching means to release the bolt or catch. More specifically described, our invention comprises opposed resiliently-pressed members separable one from the other by the insertion of a bolt or catch therebetween, a pivoted abutment engageable by the bolt or

catch entering between said members operable by one of said members to press the bolt against said member and opposed members operated by handle means for operating the opposed resiliently-pressed members to release the bolt.

Referring to the drawings, 10 indicates generally the latch casing or mounting which may be of any shape or construction 10 suitable to support the latch elements. In the present instance, the mounting or housing comprises a base plate 13 having an integral substantially right-angle extension forming an end portion 16. A plate 11 having integral extensions forming end portions 14 and 15 is secured to end portion 16 of the mounting 10 by any suitable means such as rivets 17 and 18. Plate 11 is narrower in width than the width of end portion 16 and when secured thereto a space is left between its edge 11^a and base plate 13 for reasons to be explained hereafter. It will be seen that base plate 13, end portion 16 and plate 11 with its extensions 15 20 25 30 35 40 45 50 55 60 65 70 75 80 85 90 95 100 105 110 115 120 125 130 135 140 145 150 155 160 165 170 175 adjoining portions at the corner of base plate 13 and end 16 of casing 10 are cut away to form a slot or recess 20.

We have provided means within the casing 10 which not only securely latches the bolt, but also positively and firmly clamps and holds the same on all sides to prevent rattling and which automatically takes-up and compensates for, loose play between the latch parts and latch bolt or catch. In the example illustrated, two opposed hook-shaped members 21 and 22 are pivoted in the space between plates 11 and 16 on pins or rivets 17 and 18, respectively. The hooked ends 210 and 220 of the members 21 and 22 are disposed adjacent the front or forward side of the casing (the side toward the latch bolt or catch) and normally lie almost in contact with one another in the slot or recess 20, the hook members 21, 22, being pressed toward each other by suitable spring means which, in the arrangement here illustrated, take the form of coiled springs 21^a and 22^a, respectively, the springs being confined between the casing and the respective hook members. The hook members are each provided with bent pins 21^b and 22^b, respectively, and the bent ends 14 and 15 of plate 13 are each provided with pins 21^c and 22^c respectively, these pins extending into the ends of the springs to prevent their accidental displacement.

The opposed edges of the outer extremities of the hook members are curved inwardly to provide a tapering entrance for the side of the bolt and thus facilitate the separation of the hook members 21 and 22 as the door is swung shut. One of the hook members, in this case the hook member 22, is provided at its inner or pivoted end with a right angle extension 221, forming in effect a bell-crank lever. The extension end of the hook member 22 is connected by a pivot 23 to one end of an abutment 24, the other end of which is pivoted at 17 to allow the abutment to swing across the path of the bolt. When the hook member 22 swings on its pivot it will cause the abutment member 24 to swing on its pivot. The arrangement is such that as the door is swung shut, the side of the projecting bolt enters between the hook members, forcing them apart, the member 22 causing the abutment member 24 to swing on its pivot 17 back or away from the entering bolt. After the bolt passes the hook ends 210 and 220 of the hook members, the hook ends close behind the bolt to prevent movement of the bolt in the opposite direction to open the door, the side faces of the hook members adjacent the bolt engaging and pressing against opposite sides of the bolt, and the abutment member 24 being swung on its pivot to engage the bolt and force it against the inner faces of the hook ends 210 and 220. It will be seen that this

action not only latches the bolt, but clamps it against all side movement, thus preventing rattling. In order that the bolt may be firmly clamped, the inner surfaces of the hook portions of the members 21 and 22 and the part of the abutment 24 which engages the bolt are shaped to conform substantially to the shape of the sides of the bolt which they engage so that they will have an extended bearing engagement with said bolt. We have shown our invention used in conjunction with a V-shaped bolt, substantially triangular in cross-section, but it is to be understood that any suitable shaped bolt may be used, although we consider the V-shaped bolt especially desirable because a bolt of this shape will enter the latch members very easily. The abutment member 24 is provided with a curved slot 25 through which the rivet 18 extends. It is desirable to have rivet 18, which forms a pivot for hook member 22, extend through the casing because by this construction the rivet holds plates 11 and 16 together and the rivet thus supported at its ends in these plates forms a strong rigid pivot for hook member 22. By providing the swinging abutment member 24 with the slot 25 through which rivet 18 extends, rivet 18 may be extended through the casing to hold the plates 11 and 16 together without the rivet interfering in any way with the free swinging movement of the abutment member.

To open the door, the bolt or catch must either be retracted from between the latch members or else the latch or hook members 21, 22 must be operated to open them sufficiently so that they will swing clear of the bolt when the door is opened.

We have provided means for operating the hook members to release the bolt or catch. The hook members 21 and 22 are each provided at their hook ends with laterally extending lugs 21^d and 22^d, respectively, these lugs extending into the space provided between plates 11 and 13 closely adjacent to plate 13. Extending between these lugs 21^d and 22^d are two opposed members 27 and 28 pivoted to base plate 13 of the casing 10 at 29 and 30, respectively. When these members 27 and 28 swing on their pivots they engage the lugs on the hook members to swing them to release the bolt or catch. Swinging of members 27 and 28 is caused by imparting a swinging movement to one of the members, this member in turn engaging and swinging the other member. In the present example, the member 27 is the actuating member, originally receiving the swinging movement and then transmitting this motion to member 28. As shown, member 27 is a comparatively short lever or cam, pivoted approximately at its center, the pivot 29 being relatively near the hook member

22 which member 27 operates. In order to swing the member 27, a lever or handle 31 is connected to the cam member 27 at the pivot point in such a way that when the handle is operated, the cam member is caused to swing on pivot 29. Handle 31 may be made integral with cam 27 or they may be separate pieces connected together and when made of separate pieces any desired way of connecting them together so they will turn or swing together may be used. In the example illustrated, cam 27 is recessed or transversely slotted slightly to receive the lever, the two being held together by the common pivot 29. Handle 31 is bent to extend through an arcuate slot 32 in plate 13 of the casing and is then bent again so that when the latch is mounted in the door the lever extends generally parallel to and along the inner side of the door and if desired, the handle may extend a convenient distance above the upper edge of the door. While cam member 27 is relatively short and pivoted at its center near the hook member which it operates, the pivoted lever 28 is relatively long and is pivoted at one end at 30 at a relatively long distance from the hook member 21 which it operates. Cam lever 27 is pivoted within the radius of lever member 28 and the latter is held in engagement with cam member 27 by a spring 33. This spring holds members 27 and 28 together so that in normal position they are substantially parallel to each other as they lie between lugs 21^d and 22^d of the hook members. Any form of spring and mounting may be used, although the form we have shown is very desirable because of its simplicity, durability and cheapness. Lugs 34 and 35 are struck out from plate 13 of the casing, one end of the U-shape spring being secured in an aperture provided in lug 34 and one side resting on and being supported by lug 35. The other side of spring 33 presses against lever 28, resting in a groove 36, forcing lever 28 toward member 27.

The operation of our device, briefly, is as follows: When the door is swung to close it, the bolt or catch enters the latch, forcing members 21 and 22 apart, the part 22 in turn moving the swinging abutment 24 away from the entering bolt. As soon as the bolt has passed the hook ends 210 and 220, the hook members come together to grip opposite sides of the bolt, the hook ends closing behind the bolt to prevent its movement in the opposite direction and the abutment 24 moving toward and engaging the bolt to force it against the hook ends. The bolt is thus securely clamped to prevent all side movement in addition to being securely latched. It is to be noted that during the time the bolt is being latched, the operating members 27 and 28 remain stationary, thus

avoiding unnecessary compression of spring 33 and saving the operating means from useless wear.

To open the door, the bolt must either be retracted from between the latch members or else the latch members opened to release the bolt. In the device shown, when it is desired to open the door, the handle member 31 is operated to swing it and cam member 27 on pivot 29. One end of member 27 then engages lug 22^d of hook member 22 to swing it, while the other end of cam member 27 engages and swings lever 28 against the tension of spring 33, lever 28 engaging lug 21^d of hook member 21 to swing it. As hook members 21 and 22 swing open, abutment 24 swings back away from the bolt and the door is free to swing open.

It will be observed that we have provided a very simple compact latch composed of a small number of parts easily and cheaply manufactured, yet which is exceedingly strong and durable. The bolt is easily latched, it being entirely unnecessary to slam the door to latch it, yet after the bolt is latched, the door and latch parts are firmly held to prevent all rattling or squeaking. This is true even if the door is not fitted with great care to reduce to a minimum play between the parts, making our device especially useful in connection with cheaper automobiles where, because of the cost, it is not feasible to fit the parts with such great care.

What we claim is:

35. 1. The combination with a bolt, of latch members separable one from the other and adapted to receive a bolt therebetween, and means for operating said latch members comprising opposed members pivoted to swing transversely of the latch members.

2. The combination with a bolt, of latch members separable one from the other and adapted to receive a bolt therebetween, and means for operating said members comprising opposed pivoted members, one of said pivoted members engaging one of said latch members and the other pivoted member engaging the first pivoted member and the other latch member.

50. 3. The combination with a bolt, of latch members separable one from the other and adapted to receive a bolt therebetween, and means for operating said members comprising a pivoted lever engaging one of said latch members, and cam means engaging said lever and the other latch member.

4. The combination with a bolt, of means for latching said bolt comprising members separable one from the other and adapted to receive a bolt therebetween, and means for operating such latch members comprising a pivoted lever engaging one of said latch members, cam means engaging said lever and the other latch member, and handle means for operating said cam means.

5. Latch means comprising opposed latch members separable one from the other by the insertion of a bolt therebetween, and means movable transversely of said latch members comprising cam means and an intermediate lever for operating one of said latch members.

6. Latch means comprising opposed hook members separable one from the other by the insertion of a bolt therebetween, and means engaging the hook end of one of said members for operating said member, said means movable transversely of said member.

7. Latch means comprising opposed pivoted hook members separable one from the other by the insertion of a bolt therebetween and means for operating said members comprising opposed members pivoted to swing transversely of said hook members.

8. Latch means comprising opposed pivoted hook members resiliently pressed together and separable one from the other by the insertion of a bolt therebetween, each of said members being provided with a laterally extending lug adjacent the hook end thereof, a pivoted lever engaging the laterally extending lug of one of said hook members, a cam engaging said pivoted lever and the laterally extending lug of the other hook member and a handle for operating said cam.

9. The combination with a bolt, of clamping members acting substantially at right angles to one another adapted when a bolt is moved between the same to automatically engage the bolt and substantially prevent rattling thereof, and means for operating said clamping members to release the bolt.

10. The combination with a bolt, of latching means projecting in the path of a bolt movable to allow the bolt to pass and then movable to prevent the bolt repassing, means operable by said latching means for holding said bolt in engagement with the latter, and means for operating said latching means to release the bolt.

11. The combination with a bolt, of latching means therefor comprising means projecting in the path of a bolt movable to allow the bolt to pass and then movable to prevent the bolt repassing, means movable to engage and press the bolt against said latching means, and means for operating said latching means to release the bolt.

12. The combination with a bolt, of latching means projecting in the path of a bolt movable to allow the bolt to pass and then movable to prevent the bolt repassing, said latching means adapted to press against and clamp said bolt, abutment means movable to engage and press the bolt against said latching means, and means for operating said latching means to release the bolt.

13. The combination with a bolt, of latch-

ing means movable by said bolt and adapted to hold the latter in latched position, a resiliently-pressed movable abutment, said abutment holding said bolt in engagement with said latching means, and means for operating said latch means to release the bolt.

14. The combination with a bolt, of latch means comprising members separable one from the other and provided with edges adapted to have extensive bearing engagement against the sides of a bolt therebetween, said members acting substantially at right angles to one another, and means for operating said latch means to release the bolt.

15. The combination with a bolt, of latch means therefor comprising a movable abutment, and a hook member, said bolt being movable past the hook end of said member to latch the bolt in the space between said hook end and said abutment, said abutment pressing said bolt against said hook end, and means for operating said latch means to release the bolt.

16. Latch means of the class described, comprising, opposed members separable one from the other by the insertion of a bolt therebetween, a movable abutment engageable by the bolt entering between said members and holding said bolt in engagement with said members, and means for operating one of said members to release the bolt.

17. Latch means of the class described comprising, opposed pivoted members having their opposed edges conforming substantially to the shape of a bolt inserted therebetween, spring means pressing said members toward one another, a movable abutment, said abutment adapted to press the bolt against said pivoted members, and

means for operating said members to release the bolt.

18. Latch means of the class described comprising, opposed members separable one from the other by the insertion of a bolt therebetween, a pivoted abutment engageable by a bolt entering between said members operable by one of the members to press said bolt against said member, and means for operating said members to release said bolt.

19. Latch means of the class described comprising, opposed resiliently-pressed pivoted members separable one from the other by the insertion of a bolt therebetween, a pivoted abutment engageable by a bolt entering between said members, one of said members being connected to said abutment to operate it to force said bolt in engagement with said members after entry of the bolt therebetween, and means for operating said members to release the bolt.

20. Latch means of the class described comprising opposed resiliently-pressed pivoted members separable one from the other by the insertion of a bolt therebetween, a pivoted abutment engageable by a bolt entering between said members, one of said members being connected to said abutment to operate it to force said bolt in engagement with said members after entry of the bolt therebetween, and means for operating said members to release the bolt comprising a pivoted lever engaging one of said members, cam means for engaging said lever and the other member, and means for operating said cam means.

In testimony whereof we hereunto affix our signatures.

EDWIN CROMPTON.
CHARLES L. CROOKS.
